P. P. FRAZER

STRIPPER BOX

Filed Sept. 11, 1922

Patented Oct. 21, 1924.

1,512,018

UNITED STATES PATENT OFFICE.

PINKNEY P. FRAZER, OF ST. LOUIS, MISSOURI.

STRIPPER BOX.

Application filed September 11, 1922. Serial No. 587,323.

To all whom it may concern:

Be it known that I, PINKNEY P. FRAZER, a citizen of the United States, residing in the city of St. Louis and State of Missouri,

5 have invented certain new and useful Improvements in Stripper Boxes, of which the following is a specification.

This invention relates to stripper boxes for foundry purposes and has for its object

10 to hold together in relative position, the refractory materials constituting a single or a nest of molds, preventing the casting from scabbing when the metal is poured, and to overcome the strain of the molten metal, 15 eliminating the distortion of corners and the injuring of the mold.

Another object of my invention is to provide a temporary holding mechanism of such a nature as to be easily tripped or released 20 at the intended time and being of a simple and efficient structural formation and combination of parts in a combined unit, adapted for ready and substantial connection.

Other and incidental objects will appear 25 as the description proceeds and in the drawing wherein I have illustrated the preferred embodiment of the invention, and wherein similar reference characters designate corresponding parts throughout the several 30 views: In the drawings,

Fig. 1, is a perspective view of an assembled stripper box.

Fig. 2, is a reduced perspective view of the detached frame parts uniting the hinged 35 parts and the rectangular top portion.

Fig. 3, is a reduced perspective view of the clamping frame.

Fig. 4, is a reduced perspective view of the cope and drag formation in a mold.

40 Fig. 5, is a reduced vertical section of a nest of molds for multiple castings.

Fig. 6, is a modification of the beveled clamping slide showing the same integral with the side holding frame portions.

45 The essential features in foundry practice for the impression of patterns, consist mainly in the maintenance of the parting lines to hold the same together in a relative position to prevent unsound castings. The 50 present methods prevailing to obtain these objects have proved inadequate in their provision for linear maintenance and it often occurs that the frame parts mainly used in molding operations and constituting the 55 most important appliances, had a sideway springing tendency injuring the mold.

I have overcome these obstacles in my device by constructing a stripper box, especially adapted for multiple castings, comprising a connected main frame consisting 60 of parallel spaced side members 1, 2, 3 and 4, said side members being composed of quadrantal sections, each section on the opposite side being hinged to one another, as shown at 5 and 6, comprising a composite 65 construction adjustable as a unit.

Located at a position approximately midway on the side holding frame portions 1, 2, 3 and 4, are outwardly projecting, longitudinally disposed clutch members 7 of a beveled 70 formation having their reduced portions 8 of said bevel 7 located at the upper terminals of the side holding frame members 1, 2, 3 and 4, and being integral with the same. Meeting in edgewise abutting contact and in angular alignment with the clutch member 7, are brackets 9 with looped portions 10 rigidly fastened to the side frame members 1, 2, 3 and 4, said brackets 9 projecting horizontally over the reduced portion 8 of the clutch 80 member 7 in the sufficient space in the internal projection to receive the slideable interfitting member 11 in its ascending position indicating the point of termination.

The slideable interfitting member 11 consists of rectangular bar arms constructed and arranged to completely embrace the frame portions 1, 2, 3 and 4 and slidably engage the outer surface of the beveled clutch member 7 simultaneously in the same 90 direction along parallel paths and in a plane at right angles to each other.

Briefly stated, the operation of my device is as follows:

The oppositely disposed hinged frame 95 members 1, 3 and 2, 4 with their interconnecting partition edges 16 and 17 are wedged together to form a rectangular shaped container. The compression member 11 being angularly shaped and in parallel alignment 100 with the side holding frame portions 1, 2, 3 and 4, is then downwardly pressed in edge abutting contact with the outer beveled surface of the clutch member 7 holding the frame portions 1, 2, 3 and 4 in tenacious engagement with each other, so that the cope 13 abutting with its inner surface against the the drag 14 can receive, through its refractory material, the impression of the pattern, holding the parting lines against linear or angular displacement, and allow the molten material, when poured into the gate- 110

stitch or basin 15 to completely fill all contours of the pattern without distorting any lines of the same.

In disengaging the frame portions of the stripper box from an operative into an inoperative position, the compression member 11 is pressed forward ascending against the bracket 9 and allowing the frame portions to disengage the edge abutting partitions 16 and 17. The side holding frame portions 1, 2, 3 and 4 can then be collapsed and the compression member 11 removed.

In Fig. 2, a modification in the structural elements of the stripper box are shown where the hinged parts 5 and 6 are bracket stop devices 9 are omitted, having the edge abutting terminals of the side holding frame portions 1, 2, 3 and 4 in rigid engagement with each other to receive the compression member 11 in the same functionary manner as aforescribed.

In Fig. 5, the vertical section of a stripper box conclusively shows the advantages of uniform clamping means for multiple castings where 15 represents the basin to receive the molten metal, 16 the runner distributing said metal into the nest of forms 18. The compact arrangement of the component parts in relation to the frame portions of the stripper box is clearly seen in this vertical section, where all forms of distorting elements are obliterated.

From the foregoing description taken in connection with the accompanying drawing, the advantages of the construction and of the method of operation will be readily apparent to those skilled in the art to which the invention appertains and while I have described the principles of operation of the invention together with the device which I now consider to be the best embodiment thereof, I desire to have it understood that the device shown is merely illustrative and that such changes may be made as are within the scope of the claimed invention.

What I claim is:

1. In a stripper box, the combination with a receptacle, divided into quadrantal detachable sections of oppositely disposed frame members, the sections on opposite sides being hinged to one another, each pair of hinged sections being adjustable as a unit, means for holding the hinged sections in a given relation to the face plates of the quadrantal sections.

2. In a stripper box, the combination with a receptacle, divided into quadrantal sections of oppositely disposed frame members, a clamping member adapted to be raised or lowered in unison without transverse constraint simultaneously in the same direction along parallel paths and in a plane at right

angles to each other, said clamping member consisting of an outwardly projecting rectangular band casing of composite construction, movable into and out of operative position, a series of bevel shaped clutch members on each side of the frame plates, said clutch members being operatively associated with the clamping member in edge abutting contact, brackets rigidly fastened to the edge terminals of the frame plates, the extremities of said brackets being outwardly bent and adapted for insertion of the pressure operated means for their limited movement, means for holding the joint partition members in rigid relation to each other to prevent linear or angular displacement.

3. In a stripper box construction for sand molds, two pair of hinged members said members being hinged diagonally of each other to form a receptacle having an open top and bottom and clamping means for closing the hinged members into engagement with the side walls of the sand mold.

4. In a stripper box construction for sand molds, quadrantal detachable sections arranged in oppositely disposed relation, means for hingedly connecting two of the corners diagonally opposite of each other, the other two diagonally opposite corners being non-hinged, and means for holding the hinged sections in their closed position and in engagement with the side faces of the sand mold.

5. In a stripper box construction for sand molds, a quadrantal receptacle hingedly united at two diagonally opposite corners only, and means for closing said sections into contact with the side faces of a sand mold and holding the sections in their closed in position, said means also serving to permit expansion of the quadrantal sections for releasing same from the sand mold.

6. In an expansible stripper box construction for sand molds, a pair of quadrantal detachable sections, the face plates of each quadrant being hinged to each other in diagonally opposite relation, a bevel plate fixed to each face plate and a clamping ring adapted for pressure engagement with the bevel plates for closing the face plates of each quadrantal section into engagement with the side face of a sand mold.

7. In an expansible stripper box construction for sand molds, a pair of quadrantal detachable face plate sections hingedly united in diagonally opposite relation, and means for closing the quadrantal sections into engagement with the side faces of the sand mold.

In testimony whereof, I have hereunto signed my name to the specification.

PINKNEY P. FRAZER.
